UNITED STATES PATENT OFFICE.

HERBERT D. TRAVELLER, OF CHICAGO, ILLINOIS.

ELASTIC-TREAD HORSESHOE.

SPECIFICATION forming part of Letters Patent No. 722,337, dated March 10, 1903.

Application filed January 20, 1902. Serial No. 90,566. (No model.)

To all whom it may concern:

Be it known that I, HERBERT D. TRAVELLER, a citizen of the United States, residing at Chicago, in the county of Cook and State of Illinois, have invented certain new and useful Improvements in Elastic-Tread Horseshoes, of which the following is a specification.

This invention relates to elastic-tread horseshoes, and refers particularly to the means for holding the elastic cushion or pad in place upon the under face of the shoe.

The object of the invention is to provide a means of attachment between the shoe and the elastic cushions, whereby the latter are held securely in place until it is desirable to remove them for inspection or renewal, when they may be separated from the shoe without difficulty.

A further object of the invention is to produce an elastic-tread horseshoe that is light, strong, and neat in appearance.

In the accompanying drawings, Figure 1 is a perspective under side view of a horseshoe embodying my invention. Fig. 2 is a transverse section on dotted line 22 of Fig. 1. Fig. 3 is a longitudinal section through the heel of the shoe on dotted line 33 of Fig. 2.

In the construction of a horseshoe embodying my invention I provide a metallic body portion A, similar in shape to the ordinary horseshoe, which body portion in this instance I have represented as being provided with the usual steel toe-calk A'. Each of the rear extremities of the shoe-body A is provided with a pocket A², the walls of which pocket are formed integral with the body portion A. The side walls A³ of the pocket are flanged or inwardly overhanging at their upper edges, and the bottom of the pocket A² is connected to the under face of the body portion A of the shoe by an inclined plane having the shoulder or ledge A⁴ at the point where it joins the bottom of the pocket.

Elastic pads B, formed with a semicylindrical body portion B' and with a base B² T shape in cross-section, are provided for the pockets A², the base of said pads being adapted to lie within the pockets and the forward edge of the pad to drop behind the ledge A⁴ at the forward end of each pocket. To strengthen the T-shape base B² of the pads B, I insert the metallic pins B³, vulcanized

into said base, extending crosswise thereof and being of a length just equal to the width of said base and just sufficient to enter between the side walls A³ of the pockets A². The pins B³ are firmly embedded in the substance of the base portion B² of the elastic pads B, and their purpose is to make the base rigid and stiff, so it cannot accidentally be knocked out of the pockets A². The rear end of each of the elastic pads B is square cut, the forward end inclined or rounding on its lower or contact face, the latter so that the rubber will receive the blow of impact with the ground upon its lower face rather than against its end.

In use the body portion A is secured to the horse's hoof in the usual manner and the pads B slid into the pockets through the forward open ends of said pockets. When the pad is in position, the forward end of the base thereof lies in the pocket behind the shoulder or ledge A⁴. To remove the pads from the pockets, a cold-chisel or other pointed instrument is inserted between the end wall of the pocket and the pad and said pad pried or otherwise forced out of the pocket.

Various changes may be made in the form and proportion of parts and in the details of construction of this horseshoe without departing from the spirit and scope of my invention. I therefore wish to have it understood that I do not limit myself to the specific construction herein shown and described.

I claim as my invention—

1. In an elastic-tread horseshoe, in combination, a body portion having a pocket formed at one of the rear extremities of said body portion, said pocket having overhanging side walls and a shoulder or ledge at the forward end of said pocket; and an elastic pad having a base substantially T shape in cross-section, adapted to lie in said pocket, said base being provided with transverse metallic pins of a length sufficient to extend between the side walls of said pocket.

2. In an elastic-tread horseshoe, in combination, a body portion having a pocket at each of its rear extremities, said pocket being provided with overhanging side walls, an end wall, and a shoulder at the forward end of said pocket, the body portion being connected with said shoulder by an incline; elastic pads

- having a base portion substantially T shape in cross-section and adapted to lie one within each of said pockets; and metallic pins extending transversely through said base portion, said pins being of a length sufficient to extend between the side walls of said pocket, said pad being cut substantially square at its rear end and rounded at its forward end on its contact-surface.
3. In an elastic-tread horseshoe, in combination, a body portion having a pocket formed at one of the rear extremities of said body portion, said pocket having side walls with inturned flanges at their upper edges, and a rear end wall; and an elastic pad having a base substantially T shape in cross-section, adapted to lie in said pocket, said base being provided with transverse stiffening-pins of a length sufficient to extend between the side walls of said pocket.
4. In an elastic-tread horseshoe, in combination, a body portion having a pocket formed at one of the rear extremities of said body portion, said pocket having side walls with inturned flanges at their upper edges, and a rear end wall, the bottom of the pocket and the under face of the body portion of the shoe being connected by an inclined surface; and

an elastic pad having a base substantially T shape in cross-section, adapted to lie in said pocket, said base being provided with transverse stiffening-pins of a length sufficient to extend between the side walls of said pocket.

5. A pad for elastic-tread horseshoes, having a base provided with transverse stiffening-pins embedded in the substance of and lying wholly within said base, said pad also being provided with holding-grooves on its opposite sides for receiving a means for securing said pad to the horseshoe.

6. A pad for elastic-tread horseshoes, having a base provided with transverse metallic stiffening-pins embedded in the substance of and lying wholly within said base, said pad also being provided with holding-grooves on its opposite sides for receiving a means for securing said pad to the horseshoe, the forward end of said pad being inclined from base to top and the rear end of the pad being substantially square cut.

HERBERT D. TRAVELLER.
